[57] **CLAIM**

The ornamental design for a combined table and plural tray unit, substantially as shown and described.

DESCRIPTION

FIG. 1 is a perspective view of a combined table and plural tray unit showing my design;

FIG. 2 is a perspective view taken from a point 180 degrees around the circumference from the FIG. 1 illustration;

FIG. 3 is a top plan view, the bottom surface being the same in appearance;

FIG. 4 is a view in side elevation; and

FIG. 5 is an exploded view of the article taken in perspective and showing the separable trays removed for convenience of illustration.

FIG. 1

FIG. 2

FIG. 3

FIG. 4

FIG. 5
